(57) **CLAIM**

The ornamental design for a vehicle wheel flare as shown and described.

DESCRIPTION

FIG. 1 is a driver's side perspective view of a vehicle wheel flare, illustrating my new design with the passenger side being a mirror image thereof;

FIG. 2 is a perspective view thereof;

FIG. 3 is another perspective view thereof;

FIG. 4 is another perspective view thereof;

FIG. 5 is a rear perspective view thereof;

FIG. 6 is a front view thereof;

FIG. 7 is a back view thereof;

FIG. 8 is a top view thereof;

FIG. 9 is a bottom view thereof;

FIG. 10 is a left side view thereof; and,

FIG. 11 is a right side view.

In the drawings, broken lines depict portions of the vehicle wheel flare that form no part of the claimed design. The claim is also for the passenger side (not shown), which is a mirror image of each embodiment shown herein.
